UNITED STATES PATENT OFFICE.

AUSTIN O'CONNOR, OF COLLINGWOOD, MELBOURNE, VICTORIA, AUSTRALIA.

CARBURETER.

1,201,493.

Specification of Letters Patent.

Patented Oct. 17, 1916.

Application filed April 5, 1915. Serial No. 19,240.

To all whom it may concern:

Be it known that I, AUSTIN O'CONNOR, a subject of the King of Great Britain and Ireland, and a resident of the post-town of 5 Clifton Hill, a district of the city of Collingwood, a suburb of the city of Melbourne, in the county of Bourke, State of Victoria, Commonwealth of Australia, (whose post-office address is 95 Spensley street, in the 10 said post-town of Clifton Hill,) have invented a certain new and useful Improved Carbureter for Internal-Combustion Engines, of which the following is a specification.

25 This invention relates to internal combustion engine carbureters of the type wherein a plurality of jets are employed, including a pilot or slow speed jet or device, with the 20 primary object of providing comparative ease in starting the engine and what is known as flexibility of running.

Hitherto many carbureters have been proposed embodying the constructional features referred to and it is generally recognized 25 that to easily start a petrol engine a rich explosive mixture is necessary having an excess of spirit, but that when once the engine is started a weaker mixture is both desirable and economical. It is usual with many carbureters to flood the same if an engine is 30 difficult to start in order to provide a rich mixture. This action, however, is very wasteful. In using a pilot jet for slow running it is common for an engine to fail to 35 "pick up" smoothly when changing from the pilot to a jet for faster running. This is owing to the change in the mixture and in some instances it has been proposed to temporarily enrich the mixture to overcome the 40 difficulty. Again, should the throttle be suddenly closed the spirit will, owing to its momentum, frequently continue to flow and be wasted. This materially affects economy. Further, the tuning or adjusting of a carbureter for any particular engine or purpose 45 absorbs considerable time and necessitates frequent removal, interchanging and fine adjustment of several parts. In making adjustments which affect the jets it is necessary to consider the relationship between 50 them, a pilot or slow speed jet not usually being adjusted without due consideration to the adjustment of any other jet or jets, or vice versa. The pilot jet, also, in many carbureters is not positively placed out of action 55 when its use is not required and when

temporarily in action when the engine is running fast, as for example, down hill, uses petrol or spirit to no purpose, economical running being again affected. Still further, in most instances, should a carbureter be temporarily inclined, owing to irregular road surfaces or the like, the spirit is apt to over-flow from the float chamber, jet or jets resulting in further and material waste. 6 To overcome this defect the suggestion has been made to dispose the jet or jets centrally in relation to the float chamber of the carbureter. Most carbureters, however, are comparatively uneconomical and are difficult 70 to tune for both "slow" and "fast" running thereby adversely influencing the flexibility of an engine.

The object of this invention is to provide a carbureter which it is never necessary to 75 flood and by the use of which an engine may be easily started when cold.

The invention provides for a maximum of flexibility, a minimum of petrol or other spirit consumption, does not inadvertently 80 flood upon uneven roads or inclines, and may be tuned or adjusted in a minimum of time without dismantling any parts whatever. By the invention, further, adjustments for slow and for fast or normal running may 85 be quite independently effected and do not in any way influence each other. The slow running device (the equivalent of a jet) is positively placed out of action when desired and is tuned or adjusted speedily and easily 90 without dismantling any parts. Tuning or adjusting for fast or normal running is effected with equal ease and without considering the "slow speed" adjustments.

The invention includes a waiting supply 95 of spirit to form a rich mixture when starting is attempted, a weaker mixture, adjustable in quality, being automatically provided when starting has been effected, without adjusting the throttle. Upon this mixture the engine runs slowly.

The invention also includes, in combination with the foregoing, the provision of a waiting supply of spirit to maintain the evenness of or regulate the diminishing richness of the mixture when the speed is to be increased preventing any upsetting or break in the mixture; and it automatically provides a weaker mixture, adjustable in quality, when the speed has increased or the 110 engine has "picked up."

The invention consists in preventing waste

either through the slow speed device or the main jet by retarding the supply of spirit to the slow speed device if it is brought into action when the engine is running comparatively fast, and by preventing a continuance of the flow of the spirit should the throttle be suddenly closed with the engine running at a comparatively high speed.

In tuning a carburetor according to the invention three features are considered, viz.:— slow speed, pick up, and fast or normal speed.

The invention also includes numerous constructional features two of the more important of which are, a central position of the main jet in relation to the float chamber to prevent over-flow or flooding on inclines, and the instantaneous removal of the needle valve and controlling floats from the said float chamber.

Experiment has shown that the invention is easily and quickly tuned or adjusted, is extremely economical in use and renders an engine exceptionally flexible and easy to start. But in order that this invention may be better understood reference will now be made to the accompanying sheet of drawings, which are to be taken as part of this specification and read herewith:—

Figure 1 is a sectional detail view of portion of a carburetor cover showing the means of locking the same. Fig. 2 is a longitudinal section of a carburetor according to this invention, the throttle being open. Fig. 3 is a part sectional plan of the invention. Fig. 4 is a reduced perspective view of the floats and appurtenances, separated from each other for convenience of illustration. Fig. 5 is a view of a slow speed air tube and adjusting needle. Fig. 6 is a sectional view, taken on line A, Fig. 3, showing a slow speed air tube and adjusting needle.

The invention includes a petrol or spirit delivery pipe 2 passing from a storage tank or the like and communicating with an entrance hole 3 formed in a shell consisting of a float chamber 4. Around the hole is formed a valve seating 5 engaging which is the lower coned end 6 of a needle valve 7 disposed within the float chamber. The upper end of the needle valve 7 upstands in the float chamber and carries a collar 8 having upper and lower flanges. Formed in the upper end of the needle valve may be a saw cut 9. Engaging the collar 8 between the flanges thereof are the outer ends of two arms 10, one disposed at each side of the said collar 8. The inner ends of the arms 10 are secured to a rocking cross member 11 within the float chamber. At each end of the cross member 11 is secured the upper end of a vertical member 12. Secured to the lower end of each vertical member 12 is a segmental or other float 13 of any desired character. Integral with the upper

end of each vertical member 12 is a lug 14 having therein a pin hole. Corresponding with the pin hole formed in each lug is a pin hole formed in a corresponding lug 15 carried at one end of a stationary cross member 16. This member 16 is supported by a longitudinal tube 17 passing through the float chamber 4. The tube 17 is open at each end. Engaging the pin holes and pivoting the lugs 14 of the rocking member 11 to the stationary member 16 are outturned pins 18 carried at the outer ends of the legs 19 of a spring bow 20.

Disposed across the longitudinal tube 17 is a needle valve guide 21 through which the needle valve 7 before mentioned passes.

The float chamber 4 is closed by a cover 22 having therein an air hole 23 and a central hole. Around the central hole is a depending central collar 24 having formed therein a pin hole. Passing through the pin hole is the inner end of a slide pin 25 having thereon a collar or the like 26 against which bears one end of a spring 27 encircling the said pin 25. The outer end of the spring 27 bears against an outer collar 28 depending from the cover 22 and passing around the upper edge of the float chamber 4. Outstanding from the outer collar 28 is a circumferential flange 29. The outer end of the pin 25 passes through the said outer collar 28 and is provided with a finger head 30 having formed therein a step or out-cut 31 whereby the pin 25 may be drawn outwardly and retained in its outward position by engaging the inner end of the head with the circumferential flange 29 of the outer collar 28. By slightly turning the said pin 25 the step or out-cut 31 disengages the inner end of the head 30 from the said flange 29 and permits the said pin 25 to move inwardly and lock the cover 22 as will be hereinafter more fully described.

Formed in the shell and passing from the float chamber 4 is a first slow speed spirit passageway 32 communicating with which is a second slow speed spirit passageway 33. Above the second passageway 33 is a starting well 34 formed in the shell and situated at the bottom of a slow speed mixing chamber 35.

Depending into the well 34 and passing through the mixing chamber 35 is the lower end of a slow speed air tube 36 the upper end of which has formed therein opposite air inlet holes 37. The tube 36 is removable and may be adjustable in relation to the well 34. Threaded into the upper end of the air tube 36 is the enlarged outer end 38 of a slow speed adjusting needle 39. This passes through the tube 36 and is of less diameter than the same. It is adjustable in relation to the tube 36 and is provided with a coned inner end 40 adapted to control the exit of the second slow speed passageway 33.

before referred to. Formed in the shell and passing from the slow speed mixing chamber 35 is a mixture transfer passageway 41 terminating in an elongated opening 5 or slot 42. This communicates with a stem hole formed in an upper protuberance 43 carried by an extension pipe 44 projecting from the shell. The extension pipe 44 communicates with the longitudinal tube 17 10 before referred to. Depending from the extension pipe 44 is a lower protuberance 45 having a pocket or recess therein. Carried by the extension pipe 44 is also a flange 46 whereby it is secured to the engine or induction pipe thereof.

Disposed in the stem hole and socket of the upper and lower protuberances 43 and 45 is a throttle stem 47 passing across the said extension pipe 44 and upstanding above the 20 same. Intermediately secured to the upper end of the throttle stem 47 above the extension pipe 44 is a lever 48. Pivotedly connected to one end of the lever 48 is an operating link 49. Carried by the other end of 25 the lever 48 is an adjustable limit stop which may include a screw 50.

Formed in one side of the upper end of the throttle stem 47 is an elongated opening or slot 51 corresponding with the elongated 30 opening or slot 42 formed in the upper protuberance 43 upon the extension pipe 44. Communicating with the elongated opening or slot 51 and within the throttle stem 47 is a transfer passageway 52 communicating 35 with which are two opposite outwardly and downwardly inclined delivery passages 53. The throttle stem 47 passes through a central hole formed in a throttle disk 54. This is disposed in the extension pipe 44 and is 40 removably secured to the said stem 47 in any well known way. The disk 54 is provided with inclined opposite faces 55 as is usual. Passing from each of the said faces 55 is an inwardly and upwardly inclined 45 opposite exit passage 56. The passages 56 correspond and communicate with the inclined delivery passages 53 of the throttle stem 47.

Disposed within the longitudinal tube 17 50 extending across the float chamber 4 is a removable air supply tube. This in conformation somewhat resembles two cones joined at their apices and consists of an air inlet coned end 57 and a mixture delivery 55 coned end 58, the latter adjoining the extension pipe 44 of the shell. Formed in the inlet end 57 of the air supply tube are slotways 59 to pass the needle valve guide 21 beforementioned. Formed in the top of the 60 said tube is a hole 60 below which is a jet hole 61.

Formed in the longitudinal tube 17 and corresponding with the jet hole 61 of the air supply tube is a central internally threaded 65 hole. Engaging the internal thread is the

external thread of a main or high speed jet 62 having a jointing flange 63 below which are flats 64 for engagement by a suitable box spanner. Formed through the jet 62 is a central hole or orifice 65. The said jet 70 62 at its upper end is reduced as at 66. Around the reduced end 66 is a circumferential step or shoulder 67. Upstanding from the circumferential step or shoulder is 75 a wall 68 the annular space between which and the reduced upper end 66 of the jet forms a "pick up" well. The wall 68 is higher than the reduced upper end 66 of the jet 62.

Formed in the float chamber 4 below the jet 62 is a threaded hole closed by a removable plug 69 in order to provide access to the jet when necessary.

Depending into the "pick up" well of the jet 62 and passing across the air supply tube at the junction of the apices of the cones thereof, is the lower end of a central tube 70, the tube 70 being hollow to permit air to be drawn therethrough into the well. Formed in the lower end of the tube is a plurality of opposite air openings or slots 71. The tube 70 is provided with a threaded upper end 72 having a milled finger edge 73. The upper end is threaded into a central guide 74 upstanding in the float chamber 4 from the longitudinal tube 17 extending across the same. Formed in the outer surface of the guide 74 at one side thereof is a pin pocket 75 engaged by the inner end of the retaining pin 25 of the cover 22 before alluded to. Upstanding from the top of the guide 74 are the lower ends of two opposite uprights 76 carried by the upper ends of which is a collar 77 having an internal thread. Engaging the internal 75 thread of the collar 77 is the external thread of a head 78 carried by the outer end of the stem 79 of a high speed adjusting needle, the said head 78 having a milled finger edge 80. The stem 79 passes through the central tube 70. The inner end 81 of the stem 79 is coned and controls the orifice 65 of the main jet 62 before alluded to.

With this invention petrol flows to the float chamber 4 in the ordinary way and enters the same until the floats 13 have risen a predetermined distance. As the floats rise they swing the vertical members 12 on the pivots of the out-turned pins 18, thereby partially turning the rocking cross member 11 and causing the arm 10 of the said member to descend. The arms 10 are in engagement with the collar 8 of the needle valve 7 which is closed upon its seating 5 and cuts off the supply of petrol. Should it become necessary to remove either the needle valve 7 or floats 13 or both it is only necessary to compress the legs 19 of the spring bow 20 when the floats 13 and needle valve 7 are immediately freed and may be withdrawn 10

from the float chamber 4. The saw cut 9 is provided for the purpose of grinding in the needle valve 7 when such becomes necessary. Petrol flows from the float chamber 4 through the first and second slow speed passageways 32 and 33 into the starting well 34 formed at the bottom of the slow speed mixing chamber 35. The petrol rises in the well to the level of the petrol in the float chamber 4. Before attempting to start the engine the throttle is very slightly opened disengaging the inclined faces or sides 55 of its disk 54 from the walls of the extension pipe 44. Upon the engine shaft being turned 10 for starting the engine the pistons cause a suction through the inwardly and upwardly inclined exit passages 56 of the throttle disk 54 which in turn communicate with the outwardly and downwardly inclined passages 20 53 of the throttle stem 47. The elongated opening 51 in the stem 47 is opposite or corresponds with the elongated opening 42 communicating with the mixture transfer passageway 41 of the slow speed mixing 25 chamber 35. Therefore upon the engine sucking through the said passageways 56, 53, 52 and 41 it obtains a rich mixture from the well 34 of the said slow speed mixing chamber 35. This starts the engine. When 30 the engine has exhausted the supply from the well 34 the lower end of the slow speed air tube 36 is uncovered and air passes through the inlet holes 37 of the tube, through the said tube and mixes with the petrol inflowing from the second passageway 33. It is obvious that by adjusting the slow speed needle 39 the quantity of petrol permitted to enter may be varied. The adjustment is effected without displacing any 35 parts, from the outside of the carbureter. The engine is now receiving a mixture for slow running, the throttle being but very slightly open. Air, however, is sucked through the air supply tube 57, 58 and extension pipe 44, the inclined passages 56 in the throttle disk 54 terminating at the middle of the periphery thereof in order to be disposed where the highest velocity of the incoming air occurs. Upon the throttle being 40 opened wider it is obvious that the elongated opening or slot 51 in the throttle stem 47 will immediately be closed and the slow speed mixture positively cut off. The engine continuing in its motion sucks through 45 the air supply tube 57, 58. The upper end of the main jet 62 projects into this tube. Petrol passing into the main jet 62 from the float chamber 4 overflows the reduced upper end 66 of the said jet and fills the "pick up" well thereof to the same level as the petrol level in the carbureter. The well of petrol at the upper end of the said jet 62 is thus immediately drawn upon by the inflowing air passing over it. The mixture is 50 therefore not suddenly changed and the engine does not immediately receive a weaker mixture, although the throttle has been opened. The quantity of spirit in the well is adjusted by the tube 70. As the suction of the engine continues the well of the main jet is emptied of petrol. Incoming air through the air supply tube 57, 58 passes through the openings 71 formed in the lower end of the central tube 70 and across the jet. This induces air to pass down through the tube 70 also and mix with the petrol passing from the jet orifice 65. It is obvious that the high speed adjusting needle 79 may regulate the quantity of petrol passing through the jet 62. When the engine is running at high speed the velocity of the air passing down through the tube 70 tends to prevent petrol passing from the jet 62, providing economy. When the throttle is suddenly closed, also, the construction provides economy as there is no direct suction upon the jet orifice 65 surrounded by the tube 70. The spirit or petrol does not continue to flow, as hitherto, as the tube 70 provides atmospheric pressure above the jet 62 and prevents any tendency to the formation of a vacuum. Any flow of spirit simply fills the "pick up" well. Further, should the engine be running down hill, for example, and the throttle be closed to such a position that the elongated openings 42 and 51 relative to slow speed running correspond, petrol will not be needlessly induced continuously into the engine as through the air passing at a high velocity down the slow speed air tube 36 the petrol after the starting well 34 has been emptied is forced backwardly into the float chamber 4 or prevented from flowing therefrom into the mixing chamber 35. The amount of petrol mixing with the indrawn air is negligible. 55

Having now fully described and ascertained my said invention and the manner in which it is to be performed I declare that what I claim is:—

1. An improved carbureter for internal combustion engines, consisting in the combination of means for providing a rich starting and slow speed mixture, means for retarding the delivery of the spirit to form the slow speed mixture if drawn upon with the engine running at a comparatively high speed, means for positively cutting off the slow speed mixture, means for providing a comparatively weak and high speed mixture, means for providing an air supply to proportionately retard the delivery of spirit to form the high speed mixture as the speed increases, and means for providing a rich mixture while changing from the slow speed mixture to the high speed mixture. 110

2. An improved carbureter for internal combustion engines, consisting in the combination of means for providing a rich starting and slow speed mixture, means for re- 115

tarding the delivery of the spirit to form the slow speed mixture if drawn upon with the engine running at a comparatively high speed, means for providing a comparatively weak and high speed mixture, means for providing an air supply to proportionately retard the delivery of spirit to form the high speed mixture as the speed increases, and means for providing a rich mixture 10 while changing from the slow speed mixture to the high speed mixture.

3. An improved carbureter for internal combustion engines, consisting in the combination of a float chamber, a removable air supply tube passing through said chamber, a main jet projecting into said tube, said jet having a "pick up" well formed at its upper end into which well spirit overflows from the jet, an adjustable tube depending 20 into the "pick up" well and encircling the upper end of the jet, air inlet openings formed in the tube above the jet, and a needle passing through the tube and regulating the quantity of spirit passing from the 25 jet.

4. In an improved carbureter for internal combustion engines, the combination of a float chamber having delivery passages pass-

ing therefrom, a slow speed mixing chamber communicating with the passages, said chamber having a starting well in communication with the passages, a slow speed air tube entering into the starting well, air passing through the tube in a direction opposing the entrance of spirit into the well, a needle 30 passing through the air tube and regulating the quantity of spirit entering into the well, said mixing chamber having a transfer passage passing therefrom, said passage terminating in an elongated opening or slot, a 35 throttle stem having a corresponding elongated opening or slot therein, a throttle disk carried by the stem, said stem and disk having inclined passages therein communicating with the elongated opening of the stem and the periphery of the disk, said inclined passages terminating at opposite sides of the disk and in a horizontal line with the center thereof.

In testimony whereof I have hereunto af- 40 fixed my signature in the presence of two 45 subscribing witnesses.

AUSTIN O'CONNOR.
